CLIFFORD C. BRADBURY, OF GLENCOE, ILLINOIS, ASSIGNOR TO LLOYD O. COULTER.

HAIR-WAVING DEVICE.

Application filed May 12, 1924. Serial No. 712,612.

My invention relates to hair waving devices, and more particularly to hair marcelling irons, the chief object of my invention being the provision of a hair waving device affording a greater convenience in operation and minimizing the amount of skill and experience necessary to secure satisfactory results in hair waving and marceling.

10 In that type of marcelling iron comprising a comb member, a heated core member, and a clamping member, now in use (such, for instance, as that shown in Patent No. 888,861, issued May 26, 1908, to Valentin Wex) the core member is reciprocated backwardly and then forwardly in relation to the comb member by manually operated means independently of the handles employed to actuate the clamping member. 20 One inconvenience attendant upon the use of such a device has been that the operator must manually move the core member in one direction to draw out the hair loops for the formation of one wave, and upon moving the iron into position for the succeeding wave must move the core member backwardly to draw out the succeeding loop in the opposite direction whereby the hairs are given the characteristic S-shaped Marcel waves. This is especially confusing in the instances where the operator is marcelling her own hair and performing the work before a mirror.

30 One object of my invention, therefore, is the provision of a marcelling iron wherein the reciprocating member is automatically moved forwardly and backwardly in alternating the waves, making it unnecessary for the operator to determine in which direction the reciprocating element is to be moved next.

35 A further object of the invention is the provision of means whereby the distance of reciprocation may be adjusted to produce a long or a short Marcel wave as desired.

40 These and further objects and features of my invention are set forth in detail in the following description of a specific embodiment thereof, and in the accompanying drawings, wherein—

45 Figure 1 is a view in perspective of the hair waving device, the reciprocating element being shown in its forward position and the clamping jaw being shown open.

50 Figure 2 is a longitudinal vertical section of the device of Figure 1;

55 Figure 3 is a plan view partly broken into horizontal section;

60 Figures 4, 5 and 6 are transverse vertical sections taken on the lines 4—4, 5—5, and 6—6, respectively, of Figure 3;

65 Figure 7 is a fragmentary detail of certain parts shown in Figure 2 but taken on the line 7—7 of Figure 3;

70 Figure 8 is a detail in perspective of certain parts shown in Figure 1, the outer coverings of which are broken away to reveal the reciprocating mechanism thereunder;

75 Figure 9 is a fragmentary section taken on the line 9—9 of Figure 1, illustrating the means whereby the distance the core member reciprocates is varied; and

80 Figure 10 is a detail section taken on the line 10—10 of Figure 2, showing the semi-universal connection of the rear end of the push finger with the handle.

85 The comb member 15 (Fig. 1) comprises a forwardly extending bifurcated channel member, the lateral flanges of which are toothed to form combs 16 for holding the hair against movement longitudinally of the device, a neck portion 17 (Fig. 7) and a downwardly projecting bracket arm 18.

90 The heated core member 19, which contains a suitable electric heating coil 20 with in a longitudinal bore 21, is disposed between the bifurcated portions of the comb member 15, the inner edges of these portions projecting into lateral grooves 22 which extend along the sides of the core member 95

whereby the latter is reciprocally supported upon the comb member. For lightness and cheapness of manufacture, the upper shoulders of the grooves 22 may be cut away if desired, leaving only projecting lugs 23, as shown in Fig. 1. The rear end of the core member carries an upstanding block 24 of insulation, through which lead wires 25

100 may pass to the terminals of the heating coil 20. The bottom side of the core member 19 is provided with spaced downwardly extending crescent-shaped fins 26 for the purpose of moving the loops of hair with it as it is slid along the comb member 15.

105 The clamping member 27 is in the form of a fork, the tines 28 of which extend forwardly while the shank 29 passes between the spaced sides 30 of the comb member arm 18 where it is pivoted to the latter by a pin 31, and terminates in a hollow wooden handle 32. The wires 25 are preferably led through this hollow handle 32 to keep the

wires out of the way of the moving parts and of the hair. The handle 33 for the comb member carries an obliquely disposed channel arm 34 constituting a lever pivoted at 5 35 to the lower end of the bracket arm 18. The lever 34 is swung backwardly relatively to the bracket arm 18 by means of a heavy leaf spring 36 (Fig. 2) until the web of the channel member 34 contacts the oblique end 10 37 of the bracket arm 18.

The operator grasps the device by the handle 32, running the fork of the clamping member 27 beneath a flat strand of hair and then pulls the handle 33 toward the handle 32, which swings the clamping member about its pivot 31 so that each of the tines enters the space between the core member and its adjacent comb 16—or more correctly, the comb member and its associated core member are pulled down to the clamping member 27. The tines 28 thus serve to hold the hair tightly against the lateral sides of the heated core member 19 and also to hold the hair securely in contact with the combs 15 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560

A pinion 39 is rotatably mounted upon the back plate portion 40 of the comb member 15 by means of a screw 41 which passes through the back plate and is threaded into a block 42 which fills the interior of the channel shaped comb member just forwardly of the neck portion 17, the block 42 being cut away to provide room for the pinion. The block 42 is provided on its upper side 45 with spaced grooves 43 which extend longitudinally of the device and tangentially of the pinion at each side thereof. Within the slots formed by these grooves and the plate portion 40 of the comb member are slidably mounted rack bars 44 and 45 which mesh with the pinion 39 so that as one of the rack bars is moved rearwardly, the other is moved forwardly. The rack bar 45 is secured at its forward end to the insulation block 24 by means of a screw 46 whereby rotation of the pinion 39 will effect a sliding of the core member 19. As shown in Figures 3 and 8, the flanges of the comb member 15 adjacent the neck portion are cut away 50 to provide room for the rack bars which extend into lateral grooves 47 of a later described cover plate 48. The grooves 43 in the block 42 and the grooves 47 form continuous grooves to support the rack bars in their reciprocation.

The flanges of the channel arm 34 are extended at the upper end thereof as a fork, within which are disposed the juxtaposed ends of a pusher element 49. The pivot pin 50 which passes through the fork of the channel arm and through the oversize holes in the ends of the pusher element 49 forms a semi-universal joint for the rear end thereof, light springs 51 serving to bring the sides of the pusher element into horizontal alignment. The forward end of the pusher element 49 is provided with an arcuate bridge 52, and the sides thereof are extended into downwardly pointing teeth 54 and 55. The forward ends of the rack bars 44 and 45 are cut off obliquely as at 44' and 45' to present upwardly and rearwardly inclined faces to the teeth 54 and 55 as the pusher element 49 is moved toward the racks.

As shown in Figure 4, the web of the channel shaped neck portion 17 is arcuately conformed, as is also the bridge 52, so that the pusher element may be rotated around the arcuate surface of the bridge against the light pressure of the springs 51 tending to hold it in a normal horizontal position. When the pusher element 49 is held in its rearmost position by the strong leaf spring 36, its teeth 54 and 55 lie rearwardly of but in horizontal alignment with the rear faces 44' and 45'. When the pusher element is in such position, the core member 19 will either be in its forward or rearward position. Assuming it to be in a rearward position as shown in Figure 3, when the operator, having already brought the clamping member 27 into position, continues to pull the handles 32 and 33 together, the pusher element 49 will be moved forwardly, with the result that the tooth 55 will 105 engage the inclined face 45' long before the tooth 54 will come adjacent the inclined face 44' of the other rack bar. Because of the resistance the hair loops offer to the sliding of the core member, the tooth 55 110 will dig down to the bottom of the rack bar 45 due to the cammed relation of these parts, rotating the pusher element around the arcuate surface of the bridge 17, after which the continued forward movement of the 115 pusher element 49 will push the rack bar 45 forwardly, carrying with it the core member 19. As the rack bar 45 moves forwardly, the pinion 39 will move the other rack bar 44 rearwardly. When the inclined face 44' of the other rack bar comes adjacent the tooth 54 of the pusher element, that tooth will have been elevated by the rotation of the pusher element so that it will lie above the top side of the rack bar 120 44 and consequently escape engagement therewith.

After the core member 19 has been moved forwardly to draw out the hair loops in the characteristic flat Marcel wave, the op- 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560

erator allows the handles to separate under the force of the leaf spring 36, which brings the pusher element 49 back to its original position. The operator also eases up slightly on the clamping member 27 to allow the device to be moved outwardly along the strand of hair until it is in position for the reverse loop of the wave. The operator then renewes the pressure on the clamping member 27 and continues to pull the handles together. Since the position of the racks have now been reversed, the pusher element 49 will first engage the rack bar 44 with the result that the tooth 54 will dig down along the inclined face 44', rotating the pusher element 49 clockwise (Fig. 4) and moving the other tooth 55 out of alignment with the rack bar 45. As the handles are further brought together, the rack bar 44 will be moved forwardly while the pinion 39 drives the rack bar 45 backwardly to return the core member 19 to its rearward position. The operator then allows the pusher element to be withdrawn and to be brought to horizontal alignment by the springs 51, after which the device is moved outwardly still further along the strand of hair to position it for the first loop of another wave.

30 The distance the heated core member is reciprocated relative to the comb member determines the distance the hair loops are drawn out. Consequently, by varying the distance of this reciprocation, the length of 35 the wave loops may be varied whereby the operator may produce either long or short Marcel waves. To make possible such an adjustment of the distance of reciprocation, I provide a square stop plate 56 secured 40 to the top of the core member 19 by means of a screw 57 threaded into the member and passing through a hole eccentric to the center of the square plate 56. A spring lock washer 58 tends to hold the plate against 45 rotation, but not so tightly but that it may be manually rotated to vary the distance from the screw 57 to the forward edge of the plate. As shown in Figures 1 and 9, the forward edge of the plate 56 abuts the 50 rear edge of a bridge portion 59 which connects the free ends of the combs 16. The operator thus may set the plate 56 in any one of its four positions to provide a pre-determined length for the Marcel wave.

55 The bridge 59 serves not only as a forward stop for the core member 19, but also prevents a spreading apart of the combs 16 under pressure of the clamping member 27. As shown in Figure 6, the bridge 59 is sufficiently elevated above the cross sectional contour of the core member to allow the latter to be withdrawn by removal of the screw 57 and the insulating block 24 when, for instance, the heating coil 20 is to be renewed.

It is to be observed that the block 42, which is preferably a die casting, serves effectually to guard the hair from becoming engaged in the racks or pinion, while the cover plate 48 keeps the hair from becoming entangled with the pusher element 49 or the rear end of the racks, the arcuate top portion of the cover plate serving to hold the bridge of the pusher element down against the arcuate surface of the neck portion 17 of the comb member. The cover plate 48 is secured in place by means of a forwardly extending lip 60, through which passes the pinion pivot screw 41, and by spaced ears 61 lying adjacent the downwardly extending bracket arm 18 and riveted in place by the pivot pin 31. The lateral sides of the groove portions are also preferably extended through the aperture in the flanges of the comb member as indicated at 62 to further hold the cover plate in place (Fig. 3).

Having thus described my invention, what I claim is:—

1. In a hair waving device the combination of a heating iron, means on said iron for engaging the hair to cause it to move with the iron, means for clamping the hair to hold portions of the hair against movement with the iron comprising a clamping member movable toward and away from said iron, said iron being mounted for longitudinal reciprocation relative to said clamping member, a handle for said member and a handle for said iron, actuation of the handles bringing said member toward said iron, an actuating member engaging one of said handles and moved thereby longitudinally of the iron after said clamping member has been moved into engagement with said iron, and a mechanism interposed between said actuating member and said iron for moving said iron forwardly and backwardly alternately upon successive actuations of the said handle.

2. The combination with a hair waving device, a heating iron, a member for clamping hair thereagainst, and a handle for bringing said clamping member against said iron of mechanism actuated by the handle for longitudinally reciprocating the iron relatively to the clamping member after the hair is thus clamped against the iron, said mechanism comprising an actuating element, a pair of oppositely moving actuated elements, one of which is secured to the iron, an actuating element connected to the handle and moved thereby in the direction in which said elements move and being normally positioned to engage both said actuated members, and means for causing said actuating element upon engaging one of said members, to move out of position for engagement with the other element.

3. In a hair waving device the combina-

tion of a heating iron, a hair clamping member for co-operation therewith, said member being arranged for movement toward and away from said iron and said iron being arranged for reciprocation relatively to said member after said iron and clamping member have been brought into co-operative relationship, manually engageable portions for bringing said member and iron together and for reciprocating said iron, and adjustable stop means for varying the distance through which said iron may be thus reciprocated.

4. A hair waving device comprising a base member, a hair clamping member arranged for movement towards said base, a hair engaging iron reciprocably mounted in said base for producing waves in the hair, manually engageable portions for actuating said clamping member and for thereafter reciprocating said iron, and manually adjustable stop means on said iron adapted to engage a stop on said base member for limiting the distance of reciprocation of the iron whereby the length of wave produced in the hair may be varied.

5. In a device of the class described, a base member and iron reciprocably mounted thereon, a clamping member co-operating therewith means for reciprocating the iron, an abutment on said base member, and a polygonal stop plate pivotally mounted eccentrically of its margins and adapted to engage said abutment for providing an adjustable limit for the reciprocation of said iron.

6. A hair waving device comprising a pair of co-operating hair clamping members arranged for movement toward each other, a heating iron associated with said members and arranged for reciprocation longitudinally thereof, a pair of handles secured to said members for actuating the members and for reciprocating the iron, the handle on one of said members being pivotally mounted on that member for movement relatively thereto, yielding means normally holding said handle and member in a definite relative position, an actuating member connected to said pivotally mounted handle, mechanism actuated by said element when said means yield for reciprocating said iron, and means for adjustably limiting the distance thereof when said iron is thus reciprocated, said last mentioned means permitting said handle to return to said normal position relatively to its associated member.

7. The combination in a hair waving device of clamping means, a heating iron arranged for reciprocation relative to said clamping means, manually engageable portions for reciprocating said iron, and mechanism for automatically alternating the reciprocable movement of said iron upon successive similar actuations of said handles, said mechanism comprising an actuating ele-

ment moved by said handles, a pair of oppositely reciprocating members, one of which is connected to the iron, and means for causing said element upon successive movements to engage alternate members. 70

8. The combination in a hair waving device of clamping means, a heating iron arranged for reciprocation relative to said clamping means, manually engageable portions for reciprocating said iron and mechanism for automatically alternating the reciprocable movement of said iron upon successive similar actuations of said handles, said mechanism comprising an actuating element, and a pair of oppositely moving 80 members engaged thereby, said element being normally positioned to engage both said members and being actuated by the contact of said element with one of said members for moving said element out of position for engagement with the other of said members. 85

9. The combination in a hair waving device of clamping means, a heating iron arranged for reciprocation relative to said clamping means, manually engageable portions for reciprocating said iron and mechanism for automatically alternating the reciprocable movement of said iron upon successive similar actuations of said handles, said mechanism comprising an actuating element, a pair of actuated elements, movement of one of said elements moving said iron forwardly and similar movement of the other member moving said iron rearwardly, said element being normally positioned for engaging both said elements, and means for alternating the movement of said actuating element to engage the respective elements alternately upon successive movements of said handle. 100

10. Mechanism for alternately reciprocating the iron of a hair waving device upon successive actuations of the device, comprising an actuating element reciprocated by a manually engageable portion of the device, a pair of oppositely moving members adapted to be engaged by said element, such engagement with one of the members moving the iron forwardly and engagement with the other of said members moving the iron rearwardly, cooperating engaging cam faces on said element and on said members, said element being normally positioned for engaging both members, said cam faces being so disposed that when said element engages one of said members it will be moved out of position for engagement with the other of said elements. 110

11. The combination with a hair waving device comprising hair clamping means and an iron arranged for reciprocation relatively thereto, of mechanism, including an actuating handle for automatically reciprocating said iron, comprising a pair of spaced racks in engagement with a pinion on op- 125

posite sides thereof, an actuating element moved by said handle and adapted to engage each of said racks, and means for relatively shifting said element and said racks 5 upon successive movements of said element for causing said element to engage each rack alternately, one of said racks being secured to said iron.

12. In a hair waving device the combination of a fork-shaped base member, a clamping member for co-operating therewith to clamp the hair, a heating iron reciprocably mounted on the tines of said fork-shaped member, and a bridge connecting the outer 15 end of said tines and permitting the withdrawal of said iron therebeneath, and a removable stop on said iron for abutting said bridge to limit the reciprocation of said iron.

13. The combination in a hair marcelling device of a base member, a clamping member pivoted thereto, an iron reciprocable on said base member, handles on said members for actuating the members, mechanism for reciprocating said iron, a joint in one of said handles for actuating said reciprocating mechanism, spring means for urging said members apart, and spring means for urging said reciprocating means to a normal position, said first mentioned spring means yielding before the said second mentioned spring means when said handles are actuated, whereby said members are brought together before said iron is reciprocated. 20 25 30

In witness whereof, I hereunto subscribe my name this 8th day of April, 1924.

CLIFFORD C. BRADBURY.
